UNITED STATES PATENT OFFICE.

CHARLES L. HEISLER, OF SCHENECTADY, NEW YORK.

LOCOMOTIVE-SAND-BOX ARRANGEMENT.

1,093,989.

Specification of Letters Patent. Patented Apr. 21, 1914.

Application filed February 13, 1911. Serial No. 608,475.

To all whom it may concern:

Be it known that I, CHARLES L. HEISLER, a citizen of the United States, residing at Schenectady, in the county of Schenectady 5 and State of New York, have invented certain new and useful Improvements in Locomotive-Sand-Box Arrangements, of which the following is a specification.

My invention relates to an improved form 10 of air, and hand, track sanding device, such as generally applied to locomotives; and has for its objects: First:—the reduction in the cost of manufacture; by permitting the entire air and hand sanding arrangement, 15 with the necessary air pipes and operating levers, to be made up in lots, and thereafter to be attached to any size of a simple form of sand-box casing. Second:—to permit casting in small parts the several sand 20 valve, ports, and more intricate pieces; also to simplify the molding of the large sand box casing by omitting all the intricate core-work and instead casting it in the small pieces. Third:—to simplify the ordering 25 of castings, and the making of drawings for changes in type of sanders, all of which can be readily attached to the simple form of casing without change of pattern or drawings. Fourth:—to simplify the cost of 30 maintenance by the use of a simple design of sand-box, or casing, to which any form of sander may be attached, in a few moments' time. Fifth:—to provide a combined 35 air, and hand, sander with a single sand outlet arranged in common to both and so that the hand sander valve lever may be used to clear a clogged inlet free of pebbles, or other debris, without the necessity of using a wrench and poker. Sixth:—to provide 40 an anti-clogging sander which cannot become inoperative, even temporarily, by the presence of debris in the sand. Seventh:—to increase the available sand holding capacity of the casing or box, by 45 means which will cause each air sander to collect the sand from a large area of the sand-box bottom, instead of at a single point, as in the older devices, which make available for sanding only a comparatively 50 small portion of the sand in the box without again re-distributing the sand with a shovel.

In the drawings, Figure 1, is a vertical cross-section through a sand-box showing 55 the arrangement of the valve crank shaft, air pipes, sand valves, and sand discharge

pipes. Fig. 2, is a top view of the sanding device shown in Fig. 1. Fig. 3, shows a detailed section of the sand valve and flange, when removed from the box shown in Fig. 60 1. Fig. 4, is a sectional view as indicated by the darts A B, in Figs. 1 and 2. Fig. 5, is a sectional view F G. Fig. 2, of the valve removed from the box. Fig. 6, is an exterior view of the valve flange and double sand outlets, as indicated by the dart E in Fig. 1. Fig. 7, is a double sander valve removed from the flange in Fig. 4. Fig. 8, is a sectional view of a modified form of the sander valves shown in the foregoing 70 figures, and attached to a corresponding flange; the interior views of which, indicated by the dart F, are shown in Figs. 9 and 12. Fig. 10, a sectional view on line G H. Fig. 11, is a view indicated by the 75 dart J. Fig. 13, shows a section and exterior, views of twin sand-boxes fitted with the improved device. Fig. 14, shows a diagrammatic plan view of the elongated air blast sand tubes detailed in Figs. 15, 16 and 80 17. Fig. 15 shows the same box as in Fig. 1, with the sand valve arranged on elongated air-blast sand tubes, instead of the short air-blast tube or funnel formed in the valve shown in Figs. 1, 2 and 3. Fig. 16, is a 85 cross-section at C D of Fig. 15, and shows the sand valve. Fig. 17, is a cross-section of a modified sand blast tube.

Numerals 1, 1^a and 1^b in Figs. 1, 2, 13, 14 and 15, show the dome like casing of the 90 sand-box which differs from those of usual construction in that it is provided with two circular openings 2, 2^a, 2^b, 2^c, and 2^d, shown in Figs. 1, 2, 9, 13 and 15. The common axis of these two circular openings is preferably a short distance above the bottom of the sand-box so they can be bored at one setting by means of a boring bar passing through both openings. Lugs 3, 3^a, 3^b, 3^c, 3^d, 3^e, are cast on the casing of the box and 100 project toward the center of the openings to provide a means for bolting the valve flange 4, 4^a, 4^b, 4^c, 4^d, 4^e, and 4^f, to the casings illustrated. These circular openings permit the attachment of any desirable form 105 of sander, and, as shown, are well suited for the improved type of air, and hand sander to be hereinafter described.

The arrangement for hand sanding consists of a crank shaft 5, 5^a, 5^b, arranged 110 within the casing, I, and supported by bearings 6, 6^a, 6^b, 6^c, 6^d, 6^e, 6^f, formed in the

valve flanges, and which is oscillated from the cab by means of a rod, in the usual manner for the purpose of swinging the double ported valve 7, 7^a, 7^b, 7^c, 7^d, 7^e, 7^f, away from its normal, or mid position, shown in the figures, and thereby permit the sand to flow into the discharge pipe, 8, 8^a, 8^b, 8^c, 8^d, 8^e, that carries it to the corresponding driver wheel of the locomotive. A pin, 9, 9^a, passes through the crank shaft and engages with a slot, 10, 10^a, in the valve. This construction permits the spring 11, 11^a, Fig. 1, to hold the valve tight against the flange and prevent leakage, at the same time the pin compels it to rotate with the shaft. For protection the spring is pocketed in the recessed hub of the valve. In Figs. 1, 2, 3, 4, 5, 6, 7, and 13, a pair of short air sand blast tubes, funnels or hoods 13, 13^a, 13^b, are cast directly in the valve. This blast tube forms a sand trap and prevents a flow of sand when the valve is in mid position as shown, at the same time forms a guide for the sand blown by the air jet coming from the small air nozzle 12, 12^a and 12^b. Frequently it is desirable to cast part of this sand blast tube or funnel on the valve flange 4^a, 4^b, as shown in Figs. 8, 9, 10 and 11, and arrange the valve with an adjustment for flow by means of the small slide 14 arranged over a slot 15 formed in the valve as shown in Figs. 8, 10 and 12.

To provide a means for ejecting practically all the sand from the box the air sand blast tubes 13^c are extended inwardly and radially if desired, as shown in Figs. 14 and 15. A slot, or port, 16^a, 16^b, 16^c, is cut into the top of the tube near the flange, and is covered by the valve 7^b, 7^c, as shown in Fig. 15. Elongated sand inlet port or ports 17, 17^a, 17^b, 17^c, are arranged in the tube as shown in Figs. 15 and 17, either at the sides or in the bottom. This arrangement of sand inlet ports causes the sand to flow from an extended area of the box to within reach of the air jet which blows it down the corresponding discharge pipe 8^c or 8^d.

The arrangement permits the independent use of either the hand sanding device, or air sander, which make common use of a single discharge pipe. The elongated sand inlet ports 17, 17^a, 17^b, and 17^c, prevent pebbles from clogging the flow, as the sand will continue to flow into the tube from either side of the clogged section, as proved in practice; which also shows that the operation is not in the least interrupted when sections of the tube are uncovered. The several modifications show that all the mechanism can quickly and easily be applied or removed from the casing. It can be arranged for single, double (as shown), or triple sanders and with any combination of single, or double hand sander. The device can evidently be attached to other forms of casing or sand boxes having flat, or inclined bottoms.

The air pipes 18, 18^a, 18^b, are preferably passed through the valve flanges 4, 4^a, 4^b, etc., to avoid drilling the casing. Brackets 19, 19^a, cast on the flange hold the nozzles 12, 12^a, in proper position with respect to the discharge sand outlet. The inclined crank shafts 5^b of the twin boxes in Fig. 13, are connected by a universal coupling 20.

The arrangement in Fig. 1, shows the sand valves, 7, 7^a, placed between the sand discharging outlet and the air jetting nozzle, 12, 12^a. This construction provides a ready means for removing debris, or pebbles, that may have clogged the air jet or outlet, by merely actuating the hand sanding crank shaft 5 in the usual manner; thereby saving the labor and annoyance of clearing the nozzle by loosening a plug and using a poker.

What I claim is:

1. The combination of a casing having means for filling and adaptation for storing sand or other comminuted material, a discharge outlet, a discharge conduit communicating therewith, and disposed outside of the casing, an air blast tube disposed within the casing, near the bottom thereof, and in communication with the outlet, the inner end of the tube being at a considerable distance from the outlet, means adapted to jet an air blast through the tube toward said outlet and conduit, and means adapted to admit material into the tube and blast at a plurality of points along the tube beginning near said outlet and extending for a considerable distance inward therefrom, and adapted to exhaust the material from within the casing over an extended space along the tube, for the purpose of increasing the available capacity of the casing and to prevent clogging.

2. The combination of a casing having means for filling and adaptation for storing sand or other comminuted material, a discharge outlet, a discharge conduit communicating therewith, and disposed outside of the casing, an air blast tube disposed within the casing, near the bottom thereof, and in communication with the outlet, the inner end of the tube being at a considerable distance from the outlet, means adapted to jet an air blast through the tube toward said outlet and conduit, and means adapted to admit material into the tube and blast at a plurality of points along the tube beginning near said outlet and extending for a considerable distance inward therefrom, and adapted to exhaust the material from within the casing over an extended space along the tube, a port communicating with said outlet and a manually operable valve adapted to govern said port, for the purpose of manually governing the discharge of material from the casing.

3. The combination of a casing having

means for filling and adaptation for storing sand or other comminuted material, a discharge outlet, a discharge conduit communicating therewith, and disposed outside 5 of the casing, an air blast tube disposed within the casing, near the bottom thereof, and in communication with the outlet, the inner end of the tube being at a considerable distance from the outlet, means adapted 10 to jet an air blast through the tube toward said outlet and conduit, and means adapted to admit material into the tube and blast at a plurality of points along the tube beginning near said outlet and extending 15 for a considerable distance inward therefrom, and adapted to exhaust the material from within the casing over an extended space along the tube, a port communicating with said outlet; a like constructed and oppositely disposed discharge outlet, discharge 20 conduit, blast tube, port, and manually operable valve; and a crank shaft extending horizontally through the casing and adapted to engage and actuate said valves for the 25 purpose described.

4. The combination of a casing having means for filling and adaptation for storing sand, or other comminuted material, a plurality of discharge outlets, a plurality of 30 discharge conduits communicating therewith and disposed without the casing, a plurality of air blast tubes disposed within the casing near the bottom thereof and having an intervening space between adjacent tubes 35 which extend inwardly for a considerable distance from the corresponding outlets, means adapted to jet an air blast through each tube toward the corresponding outlet and conduit, and means adapted to admit 40 material into each tube and blast at a plurality of points along each tube for the purpose of exhausting the material from within the casing over a plurality of spaces extending along the tubes, thereby increasing the 45 available capacity of the casing.

5. The combination of a casing having means for filling and adaptation for storing sand, or other comminuted material, a plurality of discharge outlets, a plurality of 50 discharge conduits communicating therewith and disposed without the casing, a plurality of air blast tubes disposed within the casing near the bottom thereof and having an intervening space between adjacent 55 tubes which extend inwardly for a considerable distance from the corresponding outlets, means adapted to jet an air blast through each tube toward the corresponding outlet and conduit, and means adapted 60 to admit material into each tube and blast at a plurality of points along each tube, a plurality of ports communicating with the outlets, manually operable valves adapted

to govern said ports for the purpose of manually governing the discharge of material 65 from the casing through the outlets.

6. The combination of a casing having means for filling and adaptation for storing sand, or other comminuted material, a discharge outlet, a discharge conduit communicating therewith and disposed outside the 70 casing, an air blast tube disposed within the casing near the bottom thereof, and in communication with the outlet, the inner end of the tube being at a considerable distance 75 from the outlet, means adapted to jet an air blast through the tube toward said outlet and conduit and means adapted to admit material into the tube and blast at a plurality of points along the tube beginning 80 near said outlet and extending for a considerable distance inward therefrom and which comprises one or more slots formed in the tube along its length and nearest its under side, and being adapted to exhaust the 85 material from within the casing over an extended space along the tube for the purpose of increasing the available capacity of the casing and to prevent clogging.

7. The combination of a sand box casing 90 having a filling inlet, and adaptation for storing sand, a plurality of discharge outlets formed in opposite sides thereof, a plurality of flanges adapted to cover said outlets, and having a plurality of valve ports 95 disposed adjacent to each other in each of said flanges, a valve engaging each flange and adapted to govern one or more of said ports, a shaft bearing formed in each of said flanges, an integral crank shaft extending through a flange and the sand box and adapted to engage said bearings and actuate the valves, and means for operating said shaft for the purpose of governing said 100 ports.

8. The combination of a sand box casing having a filling inlet, and adaptation for storing sand, a plurality of discharge outlets formed in opposite sides thereof, a plurality of flanges adapted to cover said outlets, and having valve ports, valve seats and shaft bearings formed thereon, valves engaging the seats and adapted to govern said ports, an integral crank shaft extending through a flange and the sand box and adapted to engage said bearings and actuate the valves, means for operating said shaft members formed on the shaft and adapted to engage and actuate the valves, springs supported on the shaft and adapted to engage the members 110 and hold the valves against the valve seats for the purpose described.
